UNITED STATES PATENT OFFICE.

PHILIP A. MYERS, OF ASHLAND, OHIO, ASSIGNOR TO F. E. MYERS AND BROTHER, OF ASHLAND, OHIO, A COPARTNERSHIP.

TRACK FOR DOOR-HANGERS.

No. 873,068.

Specification of Letters Patent.

Patented Dec. 10, 1907.

Application filed September 10, 1906. Serial No. 333,921.

To all whom it may concern:

Be it known that I, PHILIP A. MYERS, a citizen of the United States, residing at Ashland, in the county of Ashland and State of Ohio, have invented certain new and useful improvements in Tracks for Door-Hangers, of which the following is a specification, reference being had therein to the accompanying drawings.

10 My invention relates to tracks for door hangers, and its object is to provide a track for use with sliding door hangers, such as are commonly used on outside barn doors and the like, which can be made in sections of suitable length for handling and shipping and which can be assembled to form a continuous track which will be strong and durable and not easily distorted.

20 A further object is to provide a construction of this character which will enable me to utilize ordinary tubing, such as gas pipe, for the track sections.

25 With these objects in view my invention consists in the construction hereinafter to be described, and then more particularly pointed out in the claims.

30 In the accompanying drawings, Figure 1 is a plan view of my improved track; Fig. 2 is a sectional view taken through a supporting bracket and the tubing; and Fig. 3 is a detail view of one of the brackets.

35 In the accompanying drawings, the reference numeral 1 indicates the track proper which is composed of a series of sections 2 which may be of any suitable length. These sections, as here shown, are composed of ordinary iron gas pipe, but any suitable tubing may be utilized for that purpose, and it may be of any desired diameter. These pipes are 40 provided at each end with a longitudinal slot 3 extending a short distance into the tubing. In order to rigidly connect these sections to form a single continuous track, I construct the supporting brackets 4 as shown in the drawings, in which each of the supporting brackets comprises a base 5, adapted to be secured to the wall of the building, and provided with an outwardly extending web or plate 6, upon the outer end of which is carried a connecting head or member 7 which is preferably cylindrical in shape and adapted to enter the ends of the tubular sections. 45 These supporting members may be provided with any suitable means for adjusting them to the various sizes of tubing and for secur- 50 ing them within said tubing, but I prefer that shown in the drawings in which the cylindrical head is bored longitudinally and slotted, preferably throughout its length, as shown at 8, so that it can be compressed or 55 expanded to vary the diameter of the cylindrical connecting head. The expansion of the member 7 may be accomplished in any suitable manner, but preferably by the use of an ordinary expanding tool or a tapered bar 60 which may be driven into the end of the member 7, thereby expanding the same and causing it to firmly engage with the inner walls of the tubular track and firmly unite the parts.

70 The manner of assembling the sections to form a track will be obvious from the foregoing description. One of the supporting brackets 4 is first secured in proper position upon the wall and the end of one of the tube 75 sections placed upon the end of the cylindrical connecting member 7, the recess 3 in the end of such tube section engaging the edge of the web 6 and permitting the tubing to pass along the cylindrical connecting 80 member until its end is near the center thereof. A second bracket is then brought into engagement with the opposite end of the tube section and secured in proper relation with the first supporting bracket after which 85 the second section of tubing is placed upon the opposite end of the second connecting member and the process continued until the track is of the desired length. The recess 2 in the end of the pipe engaging the webs 6 of 90 the supporting brackets allow the tube sections to pass along the cylindrical connecting member a distance sufficient to bring the ends of the adjacent sections together, thereby forming a continuous track in which 95 the adjoining sections are flush and the track practically jointless. In setting up the track, the cylindrical connecting members may be expanded or contracted to fit the various sizes of tubing to give a driving fit 100 with such tubing; or the same may be first placed in the pipe section and then expanded to lock the same in position, thereby rendering the track rigid.

105 I wish it to be understood that I do not desire to be limited to the exact details of construction shown and described, for obvious modifications will occur to a person skilled in the art.

Having thus fully described my invention, 110

what I claim as new and desire to secure by Letters Patent, is:—

1. A track of the character described comprising a series of hollow sections, a support for said track having a connecting member of non-resilient material carried thereby and adapted to enter the ends of said hollow sections and having a slot extending from one end thereof, whereby the diameter of said 10 end may be varied, substantially as described.

2. A track of the character described comprising a series of hollow cylindrical sections, a support for said track having a hollow con-

nected member of non-resilient material 1 carried thereby, adapted to enter the ends of said sections and having a longitudinal slot extending through the entire length thereof, whereby the diameter of said connecting member may be varied, substantially as described.

In testimony whereof, I affix my signature in presence of two witnesses.

PHILIP A. MYERS.
